(57) **CLAIM**

The ornamental design for a medical loupe head set, as shown and described.

DESCRIPTION

FIG. 1 is side isometric view of a medical loupe head set;
FIG. 2 is an isometric view of the medical loupe head set;
FIG. 3 is a rear isometric view of the medical loupe head set;
FIG. 4 is a side isometric view of the medical loupe head set;
FIG. 5 is a front isometric view of the medical loupe head set;
FIG. 6 is a top isometric view of the medical loupe head set;
FIG. 7 is a bottom isometric view of the medical loupe head set;
FIG. 8 is side isometric view of the head gear component;
FIG. 9 is an isometric view of the head gear component;

FIG. 10 is a rear isometric view of the head gear component;
FIG. 11 is a side isometric view of the head gear component;
FIG. 12 is a front isometric view of the head gear component;
FIG. 13 is a top isometric view of the head gear component;
FIG. 14 is a side isometric view of the optical loupe component;
FIG. 15 is a rear isometric view of the optical loupe component;
FIG. 16 is a front isometric view of the optical loupe component;
FIG. 17 is a side isometric view of the optical loupe component;
FIG. 18 is a side isometric view of the optical loupe component;
FIG. 19 is a top isometric view of the optical loupe component;
FIG. 20 is a bottom isometric view of the optical loupe component;
FIG. 21 is a side isometric view of the lighting component;
FIG. 22 is a rear isometric view of the lighting component;
FIG. 23 is a front isometric view of the lighting component;
FIG. 24 is a bottom isometric view of the lighting component;
FIG. 25 is a top isometric view of the lighting component;
FIG. 26 is a side isometric view of the lighting component;
FIG. 27 is a rear isometric view of the lighting component;
FIG. 28 is a side isometric view of the head gear component with the optical loupe component;
FIG. 29 is a rear isometric view of the head gear component with the optical loupe component;

FIG. 30 is another rear isometric view of the head gear component with the optical loupe component;
FIG. 31 is a side isometric view of the head gear component with the optical loupe component;
FIG. 32 is a front isometric view of the head gear component with the optical loupe component;
FIG. 33 is a top isometric view of the head gear component with the optical loupe component;
FIG. 34 is an enlarged isometric view of the head gear component with the optical loupe component;
FIG. 35 is a side isometric view of the head gear component with the lighting component;
FIG. 36 is a rear isometric view of the head gear component with the lighting component;
FIG. 37 is another rear isometric view of the head gear component with the lighting component;
FIG. 38 is a side isometric view of the head gear component with the lighting component;
FIG. 39 is a front isometric view of the head gear component with the lighting component;
FIG. 40 is a top isometric view of the head gear component with the lighting component; and,
FIG. 41 is an enlarged isometric view of the head gear component with the lighting component.

The broken lines are included for the purpose of illustrating a portion of the medical loupe head set that forms no part of the claimed design.
